UNITED STATES PATENT OFFICE.

HERMAN J. SCHULTZ, OF CHICAGO, ILLINOIS, ASSIGNOR TO W. F. HALL PRINTING CO., OF CHICAGO, ILLINOIS, A CORPORATION OF ILLINOIS.

INSERTING MACHINE.

Application filed July 25, 1921. Serial No. 487,362.

To all whom it may concern:

Be it known that I, HERMAN J. SCHULTZ, a citizen of the United States, residing in the city of Chicago, county of Cook, and 5 State of Illinois, have invented certain new and useful Improvements in Inserting Machines, of which the following is a specification.

This invention relates to improvements in 10 inserting machines and relates more particularly to a machine to be used in connection with a binding machine whereby insert material is placed upon the open binders or books or pamphlets which are travelling in 15 the binding machine feed.

Among the salient objects of the invention are to provide an insert machine automatically controlled by the binding machine feed so that the inserts are fed and deposited 20 upon the open binders as they pass in the binding machine and so controlled that where there is a blank space in the binding machine, the feed of the insert machine is automatically interrupted; to provide an 25 insert machine in which the inserts are selected from a magazine singly and fed to automatic feeding rolls and bands and accurately positioned upon the binders which are subsequently closed as the binders pass 30 along in their travel in the binding machine; to provide a machine in which large or small inserts may be accurately and uniformly fed to be deposited properly in the binders; to provide a machine which is simple 35 in operation and automatic in every detail.

In the drawings:

Fig. 1 is a plan view of the machine with parts broken away.

Fig. 2 is a right side elevation showing the 40 driving mechanism.

Fig. 3 is an elevational view showing the feeding mechanism.

Fig. 4 is a plan view showing the 45 interrupting device as connected to the binder feed.

Fig. 5 is a fragmentary detail of the pull rolls.

Fig. 6 shows the interior of the pull roll 50 which is inserted in the broken-away section shown in Fig. 5.

Fig. 7 is an enlarged detail view of the feeding mechanism.

For simplicity in the specification, the side 55 of the machine which is set next to the

binding machine will be considered as the front, and the opposite side as the rear, the driving side of the machine as the left side and the opposite side the right. The machine adaptable to insert envelopes, papers or any desired insert material into the open binders of pamphlets, books, catalogs or other bound material passing along in the binding machine feed is mounted on the side of the binding machine by means of a support 1. The open binders 2 passing through the binding machine are carried along by the traveling feed of the binding machine shown diagrammatically at 3 and 3^a. The details of the binding machine are omitted 60 from the specification as they are no part of this invention. It is sufficient to say that the binder leaves of the bound material pass beneath the plate 4 and the feed bands 5 of the inserting machine. The inserting machine 65 itself comprises a magazine 6, which is supported upon the shaft 7 and adjustably regulated by means of the thumb screws 8. The angle of the magazine which controls the feed of the insert material is adjusted by 70 means of the screw 9 in the slot 10. The inserts which may comprise envelopes or papers as shown at 11 are stacked in the magazine and are weighted as shown so that they feed properly by a rod 12 pivoted to 75 the frame 13 of the inserting machine by a shaft 14. The inserts are selected singly from the magazine by means of pull rolls 15 mounted on the shaft 16. These rolls pass the inserts to upper and lower feed rolls 17 and 18 mounted on shafts 19 and 20 respectively. The feed rolls draw the inserts into 80 a position to be fed between the upper feed bands 5 and lower feed bands 21. The upper feed bands ride over pulleys 22 on shaft 23 and pulleys 24 on shaft 25. The lower feed bands 21 run over pulleys 26 on shaft 27 and pulleys 28 on shaft 29. The bands are placed a slight distance apart so that the 85 insert feed will be unobstructed and there will be no crumpling of the paper in the upper and lower bands. These feed bands may be of any desired material such as fabric or rubber, the fabric being more desirable as it permits of smoother operation. 90 The shafts carrying the pulleys for the feed bands are mounted upon secondary frames 30 extending out over the binding machine feed, the binder covers 2 passing beneath the frames and into position so that the in- 95 100 105 110

serts travelling down between the bands will be deposited accurately upon the open binder covers. The power for the machine is transferred from a shaft beneath the binder machine upon which is mounted a sprocket over which rides a chain 31 driving the sprocket 32 on the shaft 33. A gear 34 is also mounted upon the shaft and drives the gears 35 and 36 which in turn drives the gear 37 mounted on the shaft 38. This gear, through an intermediate gear 39 drives the shaft 20 through the gear 40. Upon the shaft 20 is mounted a second gear 41 which meshes with a gear 42 mounted directly above it and mounted upon the shaft 19, upon which are also mounted the upper feed rolls 17.

On the opposite or right hand end of the shaft 20 is mounted a third gear 43, which meshes with a gear 44 on the shaft 25, which carries the pulley rolls 24 for the upper feed band. On the left hand end of the shaft 25 is mounted a gear 45 which meshes with a second gear 46 on the shaft 29 carrying the pulleys 28 over which run the lower feed bands.

Describing now the feed interrupting device which is operable from the bound material which passes along in the binding machine feed, the plate 4 which is positioned horizontally above the open leaves 2 is slotted as shown at 47 and in this slot is positioned a flexible finger 48, which is pivoted on the shaft 49 supported by bearings 50 and connected by means of a link 51 to the weighted connection 52 mounted on a shaft 53 carried by bearings 54 mounted on the frame 13. As the open leaves pass along in the binding machine feed, the finger 48 contacts the leaves holding the finger in substantially horizontal position. Where there is an interruption in the binding machine feed, that is, where there is a blank space or a binder omitted, the finger 48 will drop down, rotating the shaft 49 and causing the weight 52 to rotate the shaft 53 in a clockwise manner. This rotates the upstanding projection or shoe 54^a mounted on the shaft 53 into a position where the roller 55 mounted on a pawl 56 passes over the bevelled end of the shoe and raises the pawl from engagement with the notch in the disk 57. The functioning of the pull rolls is accomplished by the action of the pawl 56 which is mounted on a disk 58. This disk 58 is fixedly connected to a gear 59 which meshes with the gear 37. Disk 58 is rotatably mounted on the shaft 16, upon which is also mounted the pull rolls 15. The disk 57 is fixedly mounted to the shaft 16 and when the shoe 54^a is rotated away from a position before the roller 55, the pawl 56 will remain in engagement with the notch in the disk 57 and cause the shaft 16 to rotate, being driven through the gears 37 and 59. When, however, the finger

48 fails to contact with the binder leaf in the binder machine, the shoe 54^a will be rotated into position so that the roller 55 will disengage the pawl from the notch in the disk 57 and due to the braking action imposed by a brake band 60 acting on the opposite end of the shaft 16, the rotation of the shaft will be stopped and the continuous feed of the inserting material interrupted. The positioning of the plate 4 and the finger 48 and the timing of the mechanism is such that the functioning of the finger 48 will operate to interrupt the depositing of the inserts in the blank spaces as they register beneath the feed bands in their travel.

The pull rolls 15 mounted on the shaft 16 comprise a shell portion 15^a which is cut away as shown at 15^b and adapted to accommodate the bridge block 61 which has a central bearing for mounting the same upon the shaft 16. About the outer periphery of the bridge block is fitted an elastic band 62, a portion of which conforms with the outer surface of the pull roll. The bridge block is slotted as shown at 63 and the elastic band instead of covering the entire bridge block as shown in Figs. 3 and 7, may be threaded through one of the slotted holders and thereby made to cover only a portion of the exposed outer surfaces of the bridge block. The purpose of shortening and lengthening the exposed elastic band is to regulate the pulling effect of the pull roll, that is, where a narrow insert such as an envelope is to be made, it is only necessary to have a short surface of the pull roll contact with an envelope to properly feed it to the feed rolls while in longer inserting material such as a sheet of paper or the like to be fed, the duration of pulling contact must be of greater length so that the sheet will be uniformly fed between the pull rolls and the lower bed roll 64. These lower bed rolls are in a position directly below the pull rolls and are stationary during the operation of the machine. They are mounted upon a lower shaft 65 by means of eccentric bearings 66. These eccentric bearings are machined as shown at 67 to be fitted by a spanner wrench whereby the rolls may be positioned at any desired distance from the upper pull roll. The eccentric bearings being positioned at both ends of the shaft 65 where the same is supported in the frame 13 furnishes a means for accurately positioning the lower bed rolls so that only a single insert can be fed between the pull rolls and lower bed rolls.

In the drawings, the lower bed roll is shown with an outer surfacing of rubber at 68 but this material is unnecessary as a wood or steel roll would serve as well. The upper feed rolls 17 are of rubber and the lower feed rolls 18 are of steel. Here again, the proper feed may be obtained by the use of

different compositions but the contact between the rubber and steel serves to satisfactorily advance the sheets so that they are fed properly between the feeding tapes.

5 The tapes travel over crowned pulleys and deposit the inserts accurately upon the open binder leaf due to the careful timing of the apparatus with the feed of the binding machine. The machines take up little space and 10 due to their automatic operation require very little attention.

I claim as my invention:

1. An inserting machine for supplying inserted material onto open binders as they 15 travel along on the conveying mechanism of a binding machine consisting in a chute positioned thereabove, means for feeding short or long inserts and adjustable to move variable sized inserted material uniformly 20 onto the binders.

2. An inserting machine for feeding inserts to the open binder, consisting in a feed chute for holding the insert material, pull rolls for selecting the insert elements 25 from the feed chute and adaptable to advance the elements to feed bands whereby the inserts are deposited onto the open binders as they advance in the feed of a binding machine.

30 3. An inserting machine consisting in a magazine containing the inserting material mounted adjacent a book binding machine, pull rolls for selecting and advancing the separate inserts, feeding means adapted to receive the separate inserts and deposit the same on the open binder as it advances 35 through the binding machine, means for interrupting the insert feed to conform with the feed of the binders.

40 4. An inserting machine consisting in a magazine chute for carrying the insert material mounted adjacent a book binding machine, pull rolls adjustable to feed short or long inserts and adapted to select the 45 inserts singly from the chute and advance the

same to a feeding means whereby the inserts are carried and deposited in each of the open binders traveling in the binding machine, means operable with said binding machine for interrupting the feed of the inserts to conform with blank spaces in the binding machine. 50

5. An inserting machine mounted adjacent a binding machine, comprising a magazine chute mounted on the inserting machine for carrying the insert material, pull rolls adjustable to feed long or short inserts and feeding means traveling in timed relation therewith adapted to receive the insert material from the pull rolls and deposit it at timed intervals upon the open binder of the stock passing along the feed of the binding machine, means for controlling the feed of the inserts to correspond to the stock traveling in the feed of the binding machine. 55

6. An inserting machine for feeding insert material on open binders fed through a binding machine, comprising a magazine chute for holding the inserts, pull rolls for 60 selecting and advancing the inserts separately, feed bands adapted to receive the inserts from the pull rolls and deposit them at timed intervals into the bound stock. 70

7. An inserting machine adapted to be 75 mounted in connection with a binding machine and to feed insert material on to the open binder fed through the binding machine, comprising a magazine chute for holding the inserts, pull rolls for selecting 80 and advancing the inserts separately, feed bands adapted to receive the inserts from the pull rolls and deposit them at timed intervals into the bound stock, an interrupting device operable from the binding machine 85 feed for interrupting the feed of the inserts corresponding with a blank space in the binding machine feed.

HERMAN J. SCHULTZ.
